UNITED STATES PATENT OFFICE

2,619,722

SEAM RIPPER

Arthur R. Ralston, Kansas City, Mo.

Application July 13, 1950, Serial No. 173,545

3 Claims. (Cl. 30—289)

1

This invention relates to a seam ripper, and has for one of its objects the production of a simple and efficient seam ripper which may be used also as a button remover and a button-hole cutter.

An important object of the invention is the removable bead or tube which is slidably connected to the blade end may be removed to allow the blade to lie flat upon the fabric at the will of the operator.

A further object of the invention is the production of a cutting blade having one guiding tube formed integral with the blade and another guiding tube detachably and frictionally secured within the first mentioned tube and extending longitudinally of the blade upon the opposite side thereof.

Other objects and advantages of the present invention will appear throughout the following specification and claims.

In the drawing:

Figure 1 is a perspective view of the seam ripper;

Figure 2 is a perspective view of the blade of the ripper, showing the removable tube removed or detached from the blade;

Figure 3 is an end elevational view of the blade illustrating the manner in which it is used while ripping a seam;

Figure 4 is a perspective view of the blade illustrating its use as a button remover;

Figure 5 is a view illustrating the manner of cutting a buttonhole by use of the ripper;

Figure 6 is an enlarged end elevational view of the blade;

Figure 7 is a side elevational view on an enlarged scale illustrating a modified form, wherein a wedge-shaped removable tube fits into a wedge-shaped channel to facilitate a firm frictional grip.

By referring to the drawing in detail it will be seen that 10 designates the blade of the tool or ripper which preferably is rectangular in shape having a shank 11. The shank 11 is adapted to fit within a suitable handle 12, although if desired the shank 11 may be used as a handle to facilitate the use or operation of the blade 10. The blade 10 is preferably formed of narrow gauge metal having sharpened edges 13 to facilitate cutting. It of course is desirable to form the blade of thin material to facilitate ripping and cutting without injury to the material upon which it is used.

The blade 10 is provided with an integral tubular open ended longitudinally extending guiding bead 14 which is pressed laterally from the blade to define a longitudinally extending channel as at

2

15. The tube 14 is preferably substantially circular in cross section, as shown in detail in Figure 6. An elongated insertable and removable guiding tube or bead 16, which is also substantially circular in cross section, is removably secured to the blade 10. The tube or bead 16 is provided with longitudinal flared resilient flanges 17 spaced from each other and which slidably and frictionally engage the inner face of the channel 15 of the tube 14. The flanges 17 are spaced and the tube 16 and flanges 17 have a spring expansion action against the inner face of the tube 14 to firmly hold the tube 16 in a set and frictionally locked position within the tube 14. It is obvious from the drawing, that the tube 16 is placed in the tube 14 and channel 15 thereof by sliding the tube 16 into one end of the channel 15 in the direction of the arrow shown in Figure 2.

If desired, the blade 10^a shown in Figure 7, 20 may be provided with a longitudinal channel 15^a similar to the channel 15, shown in Figure 2, the channel 15^a which is tapered or wedge-shaped the direction of its length to receive the bead or tube 16^a which is similar to the tube 16 with the exception that the tube 16^a is tapered or wedge-shaped the direction of its length. This wedge-shaped formation will permit the tube 16^a to be wedged into the channel 15^a to lock the tube in position.

30 It should be noted that the device may be used as shown in Figure 3, as a seam ripper, in which event the beads or tubes 14 and 16 constitute guides to hold the fabric apart while the seam is being ripped. In removing a button the beads or tubes will constitute a means for holding the blade 10 at an angle to cut the securing thread of a button. However, by removing the bead 16, the blade 10 may lie flat upon the fabric when desired, especially in close or tight fitting work.

40 The blade 10 is also adapted for use in cutting button-holes, as shown in Figure 5, when desired. The beads 14 and 16 are preferably offset relative to the longitudinal central axis of the blade 45 to define one relatively wide cutting portion and a second relatively narrow cutting portion, the narrow portion preferably being used for cutting seams and the wide portion being used for removing buttons.

50 It should be understood that certain detail changes in the mechanical construction may be employed without departing from the spirit of the invention, so long as such changes fall within the scope of the appended claims.

Having described the invention, what is claimed as new is:

1. A device of the class described comprising a blade of substantially rectangular shape having at least one longitudinal cutting edge, said blade having a longitudinally extending tubular bead formed integrally therewith and protruding laterally from one side of said blade, said bead being open at the ends and disposed intermediate the longitudinal edges of said blade whereby to define a channel, and a longitudinally extending member insertable in and removable from said channel, said member being in the form of a bead, said removable member having spaced longitudinally extending yieldable flanges projecting outwardly and divergently relative to each other, from one side of said removable member, said flanges fitting snugly in said channel and frictionally engaging the inner face of said first mentioned bead when inserted in said channel,

10

5

whereby said member protrudes laterally from said blade upon the side opposite said one side.

2. The structure specified in claim 1, including handle means removably connected to said blade.

3. The structure specified in claim 2, wherein said first mentioned bead is tapered the direction of its length.

ARTHUR R. RALSTON.
